UNITED STATES PATENT OFFICE.

JOSIAH PERCY STEVENS, OF ATLANTA, GEORGIA.

PRINTING-PRESS.

SPECIFICATION forming part of Letters Patent No. 625,210, dated May 16, 1899.

Application filed June 9, 1898. Serial No. 683,019. (No model.)

To all whom it may concern:

Be it known that I, JOSIAH PERCY STEVENS, a citizen of the United States of America, and a resident of Atlanta, in the county of Fulton and State of Georgia, have made a certain new and useful Improvement in Printing-Machines; and I hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to printing presses or machines, the improvements having more particular relation to the inking and wiping of the plates or dies of relief or plate printing machines and in moving said dies during the operation of inking and wiping and to printing position.

In the accompanying drawings, Figure 1 is a side elevation of a press, showing this device attached. Fig. 2 is an enlarged side elevation of a portion of the device. Fig. 3 is a section of the device on the line numbered 3 in Fig. 1. Fig. 4 is an end elevation of the upright whereon the presser-plate is adjustably mounted. Fig. 5 is a detail of the actuating-levers and the latches thereon in conjunction with co-operative parts. Fig. 6 is an enlarged side elevation of the wiping-tape feed mechanism, and Fig. 7 is an end elevation thereof. Fig. 8 is a detail of the mechanism for adjusting the depression limit and raising the wiping-platen. Fig. 9 is a detail in side elevation of the releasing-arm controlling the descent of the wiping-platen. Fig. 10 is an end view of the parts shown in Fig. 9. Fig. 11 is a cross-sectional view of the wiping-platen, showing a side elevation of one of the arms carrying same. Figs. 12 and 13 are respectively side and edge views of one of the main actuating-levers.

In the figures like reference characters are uniformly employed in the designation of corresponding elements of construction in all the views.

A is the press-frame. a is the base thereof. a' is a suitable substructure.

a² is the bed-plate of the press, and a³ the plunger thereof.

a⁴ is a spur-gear on the main shaft or cam-shaft of the press, and a⁵ is the pinion meshing therewith.

a⁶ is the paper-table whereon the paper is laid while inking the press.

As best shown in Fig. 3, the bed a² has at its upper side ways of any desired construction, and B is a carriage adapted on its upper side to receive the printing plate or die and fitting by its lower side into the ways on the upper side of the bed a². Secured to the end of the bed a² and having one of its faces perpendicular thereto, preferably, is an upright plate c and having on its side toward the press proper a suitable guide or bearing for the head-block c', which carries the arms C, hereinafter described, and which bear near their distal extremity the wiping-platen. This head-block c' is provided with a pin c², Fig. 4, projecting into a slot c³ in the upright c, whereby is provided a sliding fulcrum at the lower end of said head-block. In the upper end of the head-block c' is set a stud c⁴, and the upright c is provided with a hole, as shown by the broken lines c⁵ in Fig. 4, very much larger in diameter than the bolt c⁴, whereby said bolt may have movement in all directions therein. c⁶ is a washer adapted to cover the said hole and receive the bolt c⁴. This obviously provides for an adjustment of the head-block c' in all directions in its own plane. This adjustment, as will be presently plainly seen, provides an adjustment for the lower 85 or working face of the wiping-plate D. The arms C are pivoted upon a bolt c⁷, passing through a lug or lugs on the head-block c', and they extend above the base a² to the raising and lowering mechanism, which will be 90 hereinafter described. As best shown in Fig. 11, the wiping-platen consists of a metallic plate d, held between the two arms C or upon the arm C, if only one is to be used, and an elastic underlay d', of suitable material, to 95 resist the destructive action of the die impact and at the same time to afford a surface suitable to press the wiping-paper against all portions of the printing plate or die.

d² is a reel provided with suitable detent mechanism, and d³ is a strip of cloth or other suitable substance which forms an overlay for the wiping-platen to reduce the friction of the paper web thereupon should the pad

55

95

100

d' be of friction-increasing material, the said strip of fabric being wound upon the reel *d*² and having its free end held by a detent *d*⁴, which should engage said free end in any 5 suitable manner.

e is a shaft which is mounted in the housing *e'*, secured to the bed-plate *a*² and having sides and a top preferably either in the form of plates or suitable framework, and passing 10 through the free ends of the arms *C* is a screw *c*¹², resting upon the hub of the cam *e*² on said shaft and preventing the depression of the platen *D* below the point where it will properly wipe the die *b* as the same passes under 15 it and preventing its depression to a point where it would likely engage with any part of the printing plate or die or the carriage *B*. A spring *c*⁸ serves to press the platen and its lever or levers downwardly into operative 20 position to the limit allowed by the screw *c*¹², and a screw *c*⁹ serves to adjust the tension of said spring. A cross-bar *c*¹⁰ extends between the ends of the levers *C*, and on the shaft *e* is a cam *e*², which is adapted by its partial revolution in contact with the said cross-bar *c*¹⁰ 25 to raise the arms *C*, and hence the platen *D*, out of and permit its descent into operative position.

F is the ink-fountain, which sets upon the 30 upper side of the base *a*², being held in position by a spring *f* and being provided with a roller *f'*, rotating in the ink by means of a belt *f*², driven from some suitable part of the machine.

G is a roller composed of or coated with a 35 suitable absorbent material and, being journaled in the upper end of a vibrating lever *g*, fulcrumed on a stud *g'*, set in the base *a*², vibrates from a position in peripheral contact 40 with the roller *f'* into a position where the die *b* will contact with its periphery upon the retraction of the carriage *B*. Means for causing this vibratory motion of the lever *g* and the partial rotation of the shaft *e* will be presently described.

H is a pillow-block which may be situated 45 on the foundation of the machine or its frame, and *h* is a shaft journaled thereon, *h'* being a lever secured to said shaft *h* and adjustable 50 longitudinally by being made in two overlapping sections held together by adjustable bolts *h*⁵, which allow the said sections to be separated and moved longitudinally with respect to each other to lengthen or shorten the lever, 55 as desired. The free end of this lever *h'* is provided with a slot *h*², and upon a bolt *h*³, seated in this slot, is pivoted a pitman *h*⁴, which is also extensible by being made in two overlapping sections secured together by a 60 plurality of adjusting-bolts *h*¹⁰, and the other end of said pitman is connected by wrist-pins *h*⁵ with the spur-gear *a*⁴ of the press or some other suitable actuating mechanism. By means of the extensibility of the pitman *h*⁴ 65 the arc of vibration of the lever *h'* may be located, and by means of the extension of the lever *h'* the vibration of said lever, and hence

the partial rotation of the shaft *h*, may be adjusted in degree, smaller adjustments thereof being obtainable by moving the wrist-pin *h*³ 70 in the slot *h*². *I* is a short lever also secured to the shaft *h* and vibrating with the partial rotations thereof, *i* being a brace extending between the levers *h'* and *I* and preserving their proper relative positions rigidly without 75 relying solely on the torsional resistance of the shaft *h* and the rigidity of securing of the said two levers thereto to prevent a variable relative movement of said levers.

J is a lever longer than the lever *I*, loosely 80 fulcrumed on the shaft *h* and extending upwardly to a point under the bed *a*², where it is connected to the carriage *B* by means of a pitman *j*⁶, thus communicating its vibratory motion converted to a reciprocating motion 85 to the said carriage. It is necessary that this motion of the carriage should stop for a considerable period of time at one end of the way in the base *a*²—that is, the carriage should dwell under the plunger of the press a sufficient length of time for the impression to be taken. Now the motion of the carriage and of the entire device being derived from a constantly-moving source, it is necessary that the engagement between the levers *I* and *J* should 90 be disrupted at the extremity of the desired forward stroke of the lever *J*, the lever *I* continuing its motion forwardly—that is, toward the front of the machine—after this disruption and engaging the lever *J* on its return 95 from such advanced position. This operation is provided for in the following manner, namely: On the lever *I* is a slide *i*', having a lug *i*², projecting from the side of its upper end toward the lever *J*, while a lug *j* 100 is secured to the lever *J*, which lugs *i*² and *j* are capable of engagement when the slide *i*' is elevated and the lever *I* returns from its forward limit of movement. Projecting from the lower end of the slide *i*' is another lug *i*³ 105 and a spring *i*⁴, engaging the slide *i*', which acts to press said slide, and hence said lug, downwardly, so as to bring said lug *i*² into contact with the periphery of the cam *i*⁴, rotatably secured on the lever *I*, and into engagement with one of the notches *i*⁵ or *i*⁶ of said cam, which engagement acts to hold said cam in any set position. A lever *i*⁷ forms 110 means for the partial rotation of said cam manually. Obviously a partial rotation of the cam *i*⁴ in the direction of the arrow 2, Fig. 12, will lower the lug *i*² out of danger of contact with the lug *j*⁷ and prevent the lever *J* from being carried backwardly with the lever *I*. An engagement between the levers *I* 115 and *J* is had in the opposite direction by means of a latch *j*', pivotally secured to the lever *J* by an arm *j*² thereon, as best shown in Fig. 5, and which latch by its shoulder *j*³ engages with the upper end of the lever *I* as 120 same moves forwardly—*i. e.*, to the left in Fig. 1—and causes the lever *J* to move with said lever *I*. A spring *j*⁴ acts to press this latch *j*' downwardly into engaging position, a

125

130

pin j^5 , set in the frame, (see Fig. 1,) acting in conjunction with the beveled end j^6 of the latch j' to disengage said latch j' from the upper end of the lever I as soon as said lever J reaches such a position as will leave the die-carriage B under the plunger of the press in the proper position for an impression to be taken. In Fig. 5 the parts are shown in the position just after disengagement on the forward movement of the lever I .

On the pin g' , as before stated, is pivoted a lever g , carrying the inker-roller G , and on the end of the shaft e is an arm e^3 . A pitman e^4 is pivotally secured to the free end of said arm e^3 , and its other end is slotted and connected by a sliding connection to one end of the lever g . Thus a partial rotation of the shaft e , which, as before stated, raises and lowers the lever C , is accomplished by a corresponding vibratory movement of the arm e^3 , and the movement of the lever g , which swings the ink-roller G from the roller f' to the die b and back, is also accomplished by said vibratory motion of the arm e^3 through the pitman e^4 . Now in order to hold the lever C elevated during the backward movement of the die-carriage and depressing it during the forward movement of said carriage or until the die is in position for an impression to be made, thus holding the wiping-platen, respectively, out of and in wiping position at those times and to ink the roller G and the die, it is only necessary to hold the arm e^3 in the position shown in Fig. 2. This is done by means of a latch K , pivotally secured to the bed-plate c^2 or other convenient place and extending to a position above and preferably just over the edge thereof near the path of the pin k on the carriage B , and a latch K' , beveled on its lower end and pendent from the end of said latch K and lying across the path of said pin k , a pin K^2 on the latch K permitting said latch K' to swing in one direction, but holding it rigid against movement with the pin k as the carriage moves forwardly. The latch K is provided with a shoulder k^4 , which engages with a lip k^3 on the end of the pitman e^4 when the wiper-platen is elevated and the latch K depressed, so that it is obvious that as soon as the latch K is lifted by the contact of the pin k with the beveled end of the latch K' the spring c^8 will cause the wiper-platen to descend into position for wiping the die and bring the inking-roller into contact with the roller f' . In order to bring the lever e^3 to the position shown in Fig. 2, lifting said platen and bringing the inking-roller into position to ink the die, a latch L is pivotally secured to the side of the lever J , and a stud l is set in the lever e^3 or the pitman e^4 in such a position as to be contacted with by said latch on the backward motion and force the lever e^3 back to its position, engaging the latch K . In order that the impact of the lever L on the pin l may be elastic, I prefer to pivot the said latch and attach a spring l' to its end, as shown in Figs. 2, 3, and 5.

M is a spring-actuated reel, and m is a cord or chain which passes over a sheave m' and has its free end attached to the die-carriage B . This element acts to keep the said carriage in contact with the stop on which it rests during impression.

N is a cord which is attached to the lever g and is made elastic by means of a spring n , its free end being attached to the floor or to the free end of the machine, said elastic cord acting to pull the said lever g from its position shown in Fig. 2 into a position where the roller G will rest against the roller f' .

O is a lever which is pivoted or fulcrumed on the pin or stud g' , having its lower end connected by a pitman o to the lever J , whereby it will be vibrated synchronously with the said lever J . o' is a link belt which is attached to the upper end of the said lever O by one end and passes over the sprocket-wheel p on the shaft P , which said shaft is mounted in the upper bifurcation c' of the upright c of the frame. It is hence obvious that a vibration of the lever O will cause a rotation of the shaft P corresponding in number or length and direction to said vibration. Now it is desirable that the roller Q revolve only in direction of the arrow 3, Figs. 1, 6, and 6. In order to accomplish this, I mount the roller Q on a hollow shaft q , which in turn is rotatable on the shaft P , and on the end of this hollow shaft I place a ratchet-wheel q' , which is held against rotation in one direction by a pawl q^2 , engaging its dentated surface, and is caused to rotate through a ratchet-wheel p' , secured to the shaft P and rotatable therewith and with which a pawl q^3 , carried on the side of the ratchet-wheel q' , engages in one direction. Thus it will be seen that a rotation in one direction of the ratchet-wheel p will be connected through the shaft P , ratchet-wheel q' , and hollow shaft q to the roller Q . Now, as best shown in Figs. 4 and 6 another shaft R is mounted in a slot r in the arms r' , secured to the uprights c , and on this shaft are carried a multiplicity of rollers r^2 , which contact peripherally with the roller Q , being held in such contact by suitable springs r^3 , secured, preferably, to the uprights c and resting their free ends against the said shaft R or its bearing-boxes.

S are bars which are pendent from the shaft R , and preferably have their ends joined by a cross-bar s , as shown in Figs. 2 and 4. Now the wiping-paper s' comes from the reel s^2 , passing downwardly by a suitable route and across the face of the wiping-pad d' and through suitable deflecting pins or rollers s^3 , thus passing with its uninked surface in contact with the roller Q and its inked surface in contact with the wheels r^2 , which, by reason of their small bearing upon the inked surface of said paper, do not adhere to said surface as much as would a single continuous roller. The arms S act as a take-off for said wheels r^2 , and the projecting edge of the bar s prevents the paper from adhering to the

faces of said arms S, so that the paper when drawn through the machine and inked on one side will be freely delivered, and there will be no accretion thereof on any part of the machine.

The operation of this device is as follows: The die-carriage B is brought forward to a position under the plunger a^3 and the engraved or otherwise constructed die is secured 5 in a suitable manner to the upper side thereof. The parts are then moved into the position shown to ink the plate and the levers I and J are drawn back to their normal position, as are all of the other elements of the device, including the wiping-pad d' , which, together with its arms C and backing d , are elevated. Now the belt shifter or clutch or other stopping and starting device is shifted to put the machine in motion, which through the pitman 10 h^4 and the levers h' and I is started forwardly, and as the upper end of the lever I engages with the shoulder j^3 of the latch j' also carries with it the lever J, moving the die-carriage B along its ways under and in forcible contact 15 with the inking-roller G and through the pin k striking the inclined faces of the latch k' lifting the lever K and disrupting the engagement between the shoulder k^4 and the lip k^3 , whereby the lever e^3 is permitted to move forwardly, and the arms C, with the wiping-pad 20 thereon, are depressed, so that a further movement forwardly of the carriage B brings the die into contact with the under surface of the web of wiping-paper resting upon the under 25 side of said wiping-pad, thereby removing the ink from the face of the die and leaving the intaglio portions full of ink. The carriage B then progresses to the point directly under the plunger a^3 , where the impression is taken, 30 the said die resting in that position due to the fact that the inclined end of the latch j' has come into contact and been raised by the pin j^5 out of engagement with the upper end of the lever I. After the impression has been 35 taken, during which time the lever I has been moving forwardly and backwardly from and to a position alongside the lever J. Now if the lip i^2 , carried on the sliding bar i' of the lever I, is elevated the said latch will engage 40 with the lug j on the side of the lever J and carry it back to its starting-point in Fig. 1. Now when the cam i^4 is in such a position that the lug i^3 on the sliding bar i' engages the notch i^5 this lug i^2 is elevated, as aforesaid; 45 but should the impression for any reason fail of consummation the operator may with his foot press downwardly upon the lever i^7 , which will bring the cam i^4 into such a position that the said lug i^3 will engage with the notch i^6 on the periphery of said cam and the slide i' and its cam i^2 be lowered out of danger of 50 engagement with the lug j' , in which case the machine will remain at rest with the exception of the lever I, which will return to its 55 starting-point and again to its forward limit of movement, whereupon the proper revolution of the cam i^4 will again cause the levers 60

I and J to engage. When said levers are thus engaged on the backward movement of the lever I, the said lever J will obviously follow 70 it, carrying the die B backwardly to its normal position. Now if it is undesirable to have the die passed backwardly in contact with the wiping-paper the wiping-pad should be again raised, which is accomplished by bringing the 75 upper end of the latch L, carried on the lever J, into contact with the stud l , as best shown in Fig. 5, whereby the said stud, together with the lever e^3 and the cam e^2 , will be partially revolved, raising the levers through the cross-bar e^{10} , and thus lifting the wiping-pad D out of operative position. This continues until the arc of movement of the working face of the latch L shall swing out of the arc of movement of the stud l , at which time the 80 engagement between the said latch L and the stud l will obviously be disrupted and the lip k^3 be allowed to engage the shoulder k^4 , the spring k^5 rendering it certain that the lever will descend. As the carriage B passes 85 backwardly the pin k strikes the latch k' , swings it out of the way, and passes under and in contact with the inking-roller G, when it is inked both coming back and going toward the point of impression. As the lever 90 e^3 swings forwardly the pitman e^4 moves the lever g , so as to bring the inking-roller G into contact with the constantly-rotated fountain-roller f' , where it stays until the lever e^3 is moved back, as just specified. The spring n , 95 connected to the lever g , assists this motion and acts to press these two rollers into contact. Through the levers O and the pitman o the wiping-paper is fed across the wiping-platen, as hereinbefore specified. 100

The adjustment of the machine having been hereinbefore set up, it is thought unnecessary to describe it.

Having thus described my invention, what I claim as new, and desire to secure by Letters 105 Patent of the United States, is—

1. In a printing-press a press and a guideway leading thereto, a die-carriage on and adapted to traverse said guideway, a plate horizontally disposed over said guideway, two 110 arms pivotally secured over said guideway and carried on said arms, a shaft and a cam thereon adapted to engage said arms and move them vertically and means for causing a partial rotation of said shaft synchronously with 115 the movement of said die-carriage, and a set-screw in one of said arms bearing on said shaft.

2. In a printing-press, a press, and a guideway leading thereto, a die-carriage on and 120 adapted to traverse said guideway, an upright having a hole near its top and extending vertically above said guideway and secured thereto, a plate lying against the inner side of said upright, a pin projecting therefrom into said 125 hole in said upright and having a washer covering said hole, an arm pivotally secured on said plate and extending along and over said guideway, a plate secured to said arm hori- 130

zontally disposed over said guideway and means for moving said levers on their pivots upon a correlative movement of said die-carriage.

5 3. In a printing-press, a press, a guideway leading thereto, a die-carriage on and adapted to traverse said guideway a stationary plate secured to said guideway in an upright position and transversely thereof, a plate lying upon the face of the aforesaid plate, means for securing the movable plate in any set position upon and parallel to the aforesaid stationary plate, a lever pivotally secured to said movable plate, and a wiping-pad secured to 15 said lever over said guideway, and means for moving said levers on their pivots upon a correlative movement of said die-carriage.

4. In a printing-press, a press, and a guideway leading thereto, a die-carriage on and 20 adapted to traverse said guideway, an upright having a vertical slot near its bottom and a hole near its top and extending vertically above said guideway and secured thereto a plate lying against the inner side of said upright, a pin projecting therefrom into said slot and a screw entering said plate through 25 said hole in said upright and having a washer

covering said hole, a set-screw passing upwardly through said plate and into said slot and bearing its upper end upon the under 30 side of said pin, an arm uprightly secured on said plate and extending along and over said guideway and means for moving said levers on their pivots upon a correlative movement of said die-carriage.

5. In a printing-press, a press, a guideway leading thereto, a die-carriage on and adapted to traverse said guideway, a long lever pivotally secured below said guideway and connected at its upper end to said die-carriage, 40 a short lever pivoted concentrically therewith, a lug on the side of said long lever, a slide on said short lever carrying a block and a cam mounted with its periphery in contact with said slide and adapted by its rotation to move 45 said block into engagement with said lug substantially as and for the purpose specified.

In testimony whereof I hereunto affix my signature in presence of two witnesses.

JOSIAH PERCY STEVENS.
